(57) **CLAIM**

The ornamental design for a head for a golf club as shown and described.

DESCRIPTION

FIG. 1 is a perspective view of a head for a golf club showing my new design;

FIG. 2 is a front view thereof;

FIG. 3 is a right side view thereof; and,

FIG. 4 is a bottom view thereof.

The evenly spaced broken lines illustrate portions of the golf club that form no part of the claimed design. The dash-dot-dash broken lines on the drawings are included as boundary lines and form no part of the claimed design.
